KNITTING MACHINE

Thomas S. Hayhurst, Belle Harbor, N. Y., assignor
to Max Nydegger, Summit, N. J.

Original application April 13, 1944, Serial No.
530,769. Divided and this application January
25, 1945, Serial No. 574,451

1 Claim. (Cl. 66—96)

1

The present invention relates to an improvement in knitting machines. An object of said invention has been to provide a decker point construction which cooperates with latch type needles in a manner to receive stitch loops therefrom and deposit stitch loops thereon regardless of whether the latch is then open or closed. In this respect, it is therefore a more general object of the invention to provide a decker point which can be made to operate more effectively and with greater certainty than is possible with known forms of decker points.

One embodiment of my invention in a form adapted for use in connection with a flat knitting machine is described in the following specification and illustrated in the appended drawing in which—

Figure 1 is an enlarged side view with portions broken away;

Figure 2, an enlarged fragmentary top plan view of the decker point illustrated in Figure 1;

Figure 3, a fragmentary view illustrating the relative positions of a needle and a decker point and the front and rear bed combs of a flat links knitting machine when the decker point is about to engage the needle in the advanced position of said needle in decking; and

Figure 4, a fragmentary view of the parts shown in Figure 3 when the decker point is about to receive the stitch loop from the needle in decking.

As shown in the drawing, a decker point according to my invention and indicated generally by the ordinal 782 is provided with a butt 812 at one end and opposed tapered resilient tips or spring arms 813 extending from the other end and forming a longitudinal slot between them. The outer end portions of said arms are disposed at an angle to or offset from the inner end portions thereof and are also directed inwardly toward each other to close the outer end of said slot.

In operation, when the front bed needles selected for decking are moved toward the rear bed to the position of initial engagement with the decker points, the last formed stitch loops resting under the needle latches of said needles are intercepted by portions of the rear bed comb. As the needle hooks of these loop bearing needles continue to move into the rear bed slots, the arrested loops engage the needle latches and

bring them to open position, after which said loops slide past the free ends of the latches and rest upon portions of the needle shanks.

As shown in Figure 3, when the decker point as 5 782 reaches needle engaging position, it is moved downwardly and readily engages the needle hook in the slot between said tips 813, regardless of whether the latch is down, that is, closed, or rocked back to open position. As the needle returns into the front bed and the hook thereof passes the ends of a portion of the front bed comb, the latch closes down over the ends of said tips 813, Figure 4. The needle is then further withdrawn into the front bed to its retracted or neutral position, leaving the stitch loop suspended on the decker point. Thereafter the decker points with said loops suspended thereon are moved to a new position opposite the needles upon which the loops are to be deposited. For this purpose the decker points move downwardly over the exposed hooks of said needles in such a manner that the ends or tips 813 thereof come behind said hooks. In so doing said tips are spread apart to pass the latches, if the latter happen to be down.

The decker point constructed as above described permits positive and rapid actuation of the needles and points both in removing loops from needles and in placing removed loops on other needles, since it is not essential to operation of the points that the latches be open or closed when the needles are in loop delivering or loop receiving position in relation to said points.

35 The above described decker point construction is shown and described but not independently claimed in my co-pending application Serial No. 530,761, now Patent No. 2,395,814, and also in my co-pending application Serial No. 530,769, now 40 Patent No. 2,395,822, of which the present application is a division.

I claim:

45 A decker point comprising a straight portion deformed at one end to provide a rearwardly extending butt and deformed and slotted at the opposite end to provide forwardly extending spaced resilient arms integral with said straight portion and tapering toward their outer ends, said outer ends being bent inwardly toward and 50 into engagement with each other.

THOMAS S. HAYHURST.
